UNITED STATES PATENT OFFICE.

ALBERT J. DEXTER, OF INDIAN ORCHARD, MASSACHUSETTS.

GAS-ENGINE.

1,038,537.

Specification of Letters Patent. Patented Sept. 17, 1912.

Application filed June 14, 1911. Serial No. 633,058.

To all whom it may concern:

Be it known that I, ALBERT J. DEXTER, a citizen of the United States, residing at Indian Orchard, in the county of Hampden 5 and State of Massachusetts, have invented certain new and useful Improvements in Gas-Engines, of which the following is a specification, reference being had to the accompanying drawings.

10 This invention relates to gas or gasoline engines and has for its object to provide a multiple cylinder four-cycle engine of the above character which is simple and efficient in construction and extremely positive in operation.

15 A further object of the invention is to provide an engine of the above described character of such construction that a maximum of working efficiency of horse-power is obtained with a minimum of weight and vibration.

20 Another object is to provide a four-cylinder engine of the horizontal type, a horizontally disposed driven shaft, and means 25 arranged thereon for automatically controlling the inlet of the gaseous mixture to the cylinders and the exhaust of the burned gases therefrom, and means for transmitting a slow rotary movement from the relatively high speed reciprocating pistons to said driven shaft.

25 With the above and other objects in view, the invention consists of the novel features of construction, combination and arrangement of parts hereinafter fully described and claimed, and illustrated in the accompanying drawings, in which—

30 Figure 1 is a vertical longitudinal section of a gas or gasoline engine embodying my improvements; Fig. 2 is a section taken on the line 2—2 of Fig. 1; Fig. 3 is a section taken on the line 3—3 of Fig. 1; Fig. 4 is a detail section taken on the line 4—4 of Fig. 1; and Fig. 5 is a section taken on the line 5—5 of Fig. 1.

35 Referring in detail to the drawings 5 designates the vertical end supports between which the horizontally disposed cylinders are arranged, the ends of said cylinders being securely bolted to the supports. These cylinders I have designated for convenience in description, 6, 7, 8 and 9 respectively, the cylinders 6 and 8, and 7 and 9 being dia-

metrically opposed. The cylinders are open at each end, the vertical supports 5 being 55 provided with openings 10 which are in line with the inner peripheries of the cylinder walls. The supports 5 are further provided with central horizontally disposed enlargements or bearings 11 in which the 60 opposite ends of a horizontally disposed shaft 12 are mounted. Continuous rotary movement is imparted to this shaft in the operation of the engine, and such movement is transmitted through the medium 65 of balance or fly wheels 13 fixed to the opposite ends of the shaft, around which the power belts pass.

70 The center of each of the engine cylinders has formed therein a short circumferential chamber 14 in the opposite side walls of which the inlet and exhaust valves 15 and 16 respectively are seated. The short longitudinally extending inlet and outlet chambers 17 and 18 are formed on opposite sides 75 of the wall of the chamber 14 and are out of alinement. The valves 15 and 16 open and close communication between the latter chambers and the chamber 14, said valves being automatically controlled by suitable 80 means arranged on the driven shaft 12 to be later described. The wall of the chamber 17 is provided with an air inlet port 19 and a similar port 20 to which the gas or 85 gasoline supply pipe 21 which extends from a suitable source of supply is connected. An exhaust pipe 22 extends into the chamber 18. In each of the cylinders a pair of pistons 23 are arranged. These pistons reciprocate in opposite directions upon the ignition of the 90 explosive charge. The connecting rods 24 of the pistons 23 extend longitudinally through the cylinders and have their outer ends pivotally connected to the horizontal arms of the cranks 25, the other arms of 95 which are cylindrical in form as indicated at 26 and are rotatably mounted in the bearing sleeves 27 formed upon the shaft bearings 11. Upon the ends of these cylindrical arms of the cranks 25 the beveled 100 pinions 28 are fixed, said pinions meshing with the teeth of the beveled gears 29 keyed upon the horizontally disposed driven shaft 12. It is the principal object of my invention to transmit continuous rotary movement 105 from the reciprocating pistons 23 to

the shaft 12 and at a reduced speed. This is accomplished through the medium of the co-acting pinions 28 and gears 29 and by properly timing the explosions in the various cylinders of the engine so as to utilize the full expansive force of the exploded gases, and eliminate to the greatest possible extent, undue waste of energy. To the above end I provide the stationary plates 30 which are centrally bored or provided with openings to receive the shaft 12 and are rigidly fixed to the several engine cylinders. Upon the outer end faces of these plates the cam lugs 31 are formed. To the shaft 12 the disks 32 are keyed as indicated at 34 and also have lugs 35 formed upon their faces which are opposed to the plates 30, and adjacent to the shaft 12. These lugs are adapted to successively engage the cam lugs 31 on the plates 30 in the rotation of the shaft 12 whereby the disks 32 are moved longitudinally upon said shaft against the tension of the coiled springs 36 which are arranged between the disks and the collars 37 fixed upon the shaft. The disks 32 are further provided adjacent to their outer edges with the lugs 38 which are formed upon the same faces of the disks as the lugs 35. The lugs 31 correspond in number with the engine cylinders, and the lug 38 on one of the disks 32 is adapted to engage the valve stems 15' to open the same and admit a mixture of gas and air to the cylinder chamber 14. The other of the disks 32 controls the exhaust valves in a similar manner, the lug 38 engaging with the valve stems 16' to open the valves 16 and exhaust the burned gases from the engine cylinders. Coiled springs 39 are arranged upon the valve stems 15' and 16' and normally act to yieldingly hold the valves upon their seats. A spark plug 40 of any preferred form is arranged in each of the cylinder walls at a point opposite the chambers 14 and is adapted to explode the compressed gases in the central portion of the cylinder. The explosion of the gases in the respective engine cylinders is properly timed so that no two explosions occur simultaneously. This timing means consists of the disk or collar 41 which is rigidly fixed upon the shaft 12 and has formed upon its peripheries the cam lug 42. This lug is adapted to engage the resilient metallic contact plates 43, and these plates are so disposed with relation to the lug 42 that the electric circuit is connected to create the spark at the proper time in the movement of the pistons in the respective cylinders. These springs are fixed upon bolts 44 arranged in the stationary plates 30 and properly insulated therefrom. The plates 43 are connected by means of suitable wiring to the spark plug 16, through an electric battery and a spark coil or other spark generator, and in the operation of the en-

gine, the electric circuit is connected through the collar 41, shaft 12, support 5 and the engine cylinder to the outside of the spark plug, across the spark gap and through the connecting wires, battery and spark coil to the spring plates 43.

The operation of my improved engine is as follows: As shown in Fig. 1 of the drawings, the gaseous mixture has been compressed in the cylinder 6, the inlet and exhaust valves of said cylinder both being closed and the charge on the point of being exploded. In the lower cylinder 8, the pistons have just completed their inward movement and exhausted the burned gases of the previous explosion from the cylinder, the exhaust valve 16 having also just closed. As the cam lug on the collar 41 contacts with the spring plate 43 the electric circuit is connected, the spark created and the charge exploded in the cylinder 6 so that the pistons 23 therein are driven outwardly in opposite directions, thereby rotating the vertically disposed cylindrical arms of the cranks 25 and through the intermeshing pinions 28 and gears 29 rotating the driven shaft 12. This rotative movement is of course, also imparted through the medium of the remaining pinions 28 to the other of the cranks 25, and the pistons 23 in the cylinder 8 which is diametrically opposed to cylinder 6 are also moved outwardly. At this point, or immediately after the charge is exploded in cylinder 6, the valve operating disk 32 is moved upon the shaft 12 and opens the inlet valve of the cylinder 8 to admit the air and gas thereto, so that, in the outward movement of the pistons in the cylinder 8 the gases are drawn into said cylinder. This opening of the valve is effected by the engagement of the lug 38 with the valve stem when the disk 32 is returned to its normal position by the spring 36.

The crank arms 25 which are connected to the rods 24 of the pistons in cylinders 7 and 9 are disposed opposite to the crank arm shown in Fig. 1 or, in other words, the pistons in said latter cylinders are at the outer ends of the cylinders at the reverse end of the stroke to those shown in Fig. 1. Through the medium of the last mentioned crank arms, the pistons in cylinders 7 and 9 are moved inwardly upon the explosion taking place in cylinder 6, and simultaneously therewith the exhaust of cylinder 7 is automatically opened so that said cylinder is cleansed in the inward movement of the pistons. In cylinder 9, compression of the gases takes place, both the inlet and exhaust valves remaining closed. The arrangement of the timing mechanism and the valve operating means upon the shaft 12 is such that the same action takes place in each cylinder to complete the cycle, as above set forth, in the following order: first, explosion in cyl-

inder 6, charge enters cylinder 8 through the opening of the inlet valve, exhaust from cylinder 7, and compression for the next explosion in cylinder 9; second, explosion in cylinder 9, compression in cylinder 8, charging in cylinder 7 and exhaust from cylinder 6; third, explosion in cylinder 8, compression in cylinder 7 charging in cylinder 6, and exhaust from cylinder 9; and fourth, 5 explosion in cylinder 7, compression in cylinder 6, charging in cylinder 9 and exhaust from cylinder 8. The fifth or next explosion takes place in cylinder 6 as in the first instance, and the cycle is repeated.

10 15 From the above description it will be observed that a charge is exploded and gases are admitted simultaneously in opposed cylinders, in which the pistons 23 are upon their outward stroke while in the remaining 20 two cylinders, the pistons move upon their inward strokes. It will therefore be seen that continuous rotary movement is transmitted from the reciprocating pistons to the power shaft 12. A very high speed of the 25 pistons is essential and desirable, while a relatively low speed of the driven shaft 12 is also desirable in many instances. The pistons in opposite cylinders moving in the same direction will absorb some of the 30 shock, and thereby lessen vibration. As the explosion in the cylinders of my engine takes place in the central portions thereof, and the cylinders are open at their ends, so that there is no pressure upon the cylinder 35 heads as in the ordinary engine construction, the vibration of the parts is further reduced, and the expansive action of the gases upon the opposed pistons, which exerts substantially the same pressure thereon, and 40 moves the pistons in opposite directions is also a further contributory feature of my construction to the elimination of vibration.

45 It is believed that from the foregoing description taken in connection with the accompanying drawings, the construction and manner of operation of my improved engine will be fully understood.

50 The device is comparatively simple, very positive in its action and extremely strong and durable in construction.

55 It will be understood that the form and manner of assembling the various elements may be greatly varied or modified without departing from the essential feature or sacrificing any of the advantages of the invention. It will further be obvious that the same principle may be applied to a two or six-cylinder engine, or any other multiple which it may be desired to employ for special purposes.

60 Having thus described the invention what is claimed is:—

1. In an engine of the character described, a plurality of horizontally disposed cylinders, each having reciprocating pistons

therein and provided with inlet and exhaust ports, a rotatably mounted shaft arranged in parallel relation to said cylinders, plates connecting said cylinders through which the shaft extends, valves normally closing the 70 inlet and exhaust ports of the cylinders, means rotatable with said shaft and longitudinally movable thereon to open said valves at predetermined times, and additional means co-acting with said last named means 75 to move the same longitudinally on the shaft, whereby the opening of the valves is effected.

2. In an engine of the character described, a plurality of horizontally disposed cylinders, each having oppositely reciprocating pistons therein and provided with inlet and exhaust ports, a rotatably mounted shaft, valves normally closing said inlet and exhaust ports, valve engaging members longitudinally movable on said shaft to open said valves at predetermined times, springs yielding holding said members against longitudinal movement and adapted to return the same to their normal positions, and stationary means co-acting with said movable members to move the same longitudinally on the shaft, whereby the opening of the valves is effected.

3. In an engine of the character described, a plurality of horizontally disposed cylinders each having oppositely reciprocating pistons therein and centrally provided with inlet and exhaust ports, a rotatably mounted shaft arranged in parallel relation to said cylinders, stationary plates connecting said cylinders, disks longitudinally movable on said shaft, said plates having cam lugs formed thereon, said disks engaging said cams whereby said disks are moved in one direction on the shaft, springs acting to return the disks to their normal positions, and a lug formed upon each of said disks at their peripheries to engage the stems of said valves and automatically open the same at a predetermined time.

4. In an engine of the character described, a plurality of horizontally positioned cylinders, each of said cylinders being open at each end and having oppositely reciprocating pistons, therein and centrally provided with inlet and exhaust ports, spring seated valves normally closing said ports, the stems of said valves being longitudinally disposed, a shaft rotatably mounted and disposed in parallel relation to said cylinders, stationary plates arranged between the cylinders and fixed thereto, said shaft extending through said plates, said plates having cam lugs formed thereon, spring held disks keyed on said shaft for longitudinal movement and normally engaging said plates, said disks each having a spaced lug formed thereon, said disks having additional lugs formed thereon co-acting with the cam lugs on said

stationary plates whereby said disks are moved longitudinally against the tension of the springs, said springs returning the disks to their normal positions and engaging the lugs thereof with the valve stems to automatically open the same at a predetermined time.

In testimony whereof I hereunto affix my signature in the presence of two witnesses.

ALBERT J. DEXTER.
